LOW WATER CONTROL FOR STEAM BOILERS

Ernest W. Loeser, Short Hills, N. J.

Application June 3, 1937, Serial No. 146,231

4 Claims. (Cl. 200—84)

This invention relates, generally, to improvements in control apparatus actuated by water level conditions in steam boilers, especially boilers and furnaces of the house heating type; and 5 the invention has reference, more particularly, to a novel control apparatus of the kind mentioned, which is adapted to open and close an electric circuit supplying power to the fuel burner apparatus of the boiler, to a feed water pump 10 apparatus, or to means for actuating feed water admission valve mechanism, as the case may be.

The invention has for an object to provide a water level actuated control apparatus including a float chamber, adapted for connection in communication with the water compartment of a boiler, and a float within said chamber, together with means for both mounting the float for oscillation within the chamber, while at the same time sealing said chamber at the point where the 20 float arm projects exteriorly therefrom; said latter means comprising a metallic bellows so constructed as to be freely flexible, to permit operative swing of the float and its arm, while at the same time being strongly resistant to longitudinal contraction and expansion under high or low pressures communicated to the chamber interior, to the end that operative condition of the float is assured at all times, and the operative relation of the exterior end of the float arm to 25 switch means adapted to be controlled thereby is maintained against derangement.

Other objects of this invention, not at this time more particularly enumerated, will be understood from the following detailed description 30 of the same.

An illustrative embodiment of the invention is shown in the accompanying drawings, in which:—

Fig. 1 is an elevational view of the low water 40 control means operatively mounted in connection with a boiler to be served thereby; Fig. 2 is a vertical section through the same, taken on line 2—2 in Fig. 1; Fig. 3 is an enlarged face view in part, with cover cap of switch compartment removed; and Fig. 4 is an enlarged sectional view of the novel flexible sealing support for mounting the float and its arm in operative relation to the float chamber.

Similar characters of reference are employed 45 in the above-described views, to indicate corresponding parts.

Referring to the drawings, the float chamber of the apparatus is preferably made in two sections, viz., an inner section 10 and an outer section 11, the same being secured together by bolts

12. The joint between the sections 10 and 11 is sealed by an interposed gasket 13. The assembled sections provide an interior closed chamber 14.

The float chamber is preferably mounted in 5 connection with the boiler 15 in association with the water level gauge glass fixture 16 with which the boiler is provided, and to this end suitable pipe fittings connect the bottom portion of the chamber 14 with the lower pipe connection 17 10 leading from the boiler 15 to the lower portion of the gauge glass fixture. As shown, these fittings comprise a T 18 which is included in said lower pipe connection 17 and a branch pipe 19 which extends between said T 18 and the lower 15 port 20 formed in inner section 10 of said chamber 14. Similarly, suitable pipe fittings connect the upper portion of the chamber 14 with the upper pipe connection 21 leading from the boiler 15 to the upper portion of the gauge glass fixture. 20 As shown, the latter fittings comprise a vertical pipe 22 which extends from the upper port 23 formed in inner section 10 of said chamber 14, and to the upper end of which is connected, by an elbow 24, a branch pipe 25 which extends 25 to a T 26 which is included in the upper pipe connection 21 of the gauge glass fixture. By the connecting arrangement thus provided, the float chamber is so disposed as to receive water from the boiler 15 in such manner that said float 30 chamber is substantially filled with water when the water in the boiler, and correspondingly in the gauge glass, stands at a normal desired level.

The outer section 11 of the float chamber 14 is provided with an outer face wall 27, from 35 the exterior side of which projects an annular flange 28. Upon the exterior of said face wall 27 is mounted an electric circuit control switch to be hereinafter more particularly described. The switch mechanism is enclosed within a removable cover-cap 29 which is telescopically engaged over and suitably secured to said annular flange 28.

Located within the interior of the float chamber 14, so as to be buoyantly supported by the 45 water content thereof, is a float member 30, preferably in the form of a hollow metallic ball, to the stub 31 of which is secured a float arm 32.

The novel means for mounting the float member for oscillation under the rise and fall of 50 water level within the float chamber, while at the same time maintaining a water-tight seal where the exteriorly projecting portion of the float arm extends through the float chamber wall, comprises the following structure:

A threaded bushing 33 having an enlarged or flanged inner end 34 is threaded from the inner side outwardly through the face wall 27 of chamber section 11, until its flanged inner end 34 abuts said wall; a sealing gasket 35 being interposed between the wall and said flanged inner end 34. Said bushing is provided with a bore 36 extending axially therethrough, a portion 37 of which is of reduced diameter. Extending into the reduced portion 37 of the bushing bore is the outer neck portion 38 of an internal tubular bellows element 39. Said neck portion 38 is suitably secured and joined to the bushing 33 so as to provide a leak-proof joint. Said internal bellows element 15 39 is provided at its opposite end with an inner neck portion 40, within which is mounted an end plug 41, the same being suitably secured and joined thereto so as to provide a leak-proof joint. Said end plug 41 is threaded to receive the float 20 arm 32, which is suitably secured thereto, preferably by a threaded connection as shown. Said float arm 32 is provided with an extension 42 of reduced diameter which passes through the end plug 41 and thence downwardly through the interior passage of said bellows element 39 and through the outer open end of the internal bushing element 37 and the bore of bushing 33. Preferably said extension 42 terminates in a further reduced extremity to form an actuator finger 43. 25 Surrounding said internal bellows element 39, so as to be disposed in spaced concentric relation thereto, is an external bellows element 44. Secured to and between adjacent ends of the internal and external bellows members 39-44 are end- 30 plates 45, these parts being so secured and joined together, as by brazing, soldering or like means, as to provide leak-proof joints, thus forming intermediate the internal and external bellows elements a closed and sealed annular chamber 40 which is filled with a suitable fluid material L such e. g. as oil of desired viscosity, alcohol, or other liquid.

It will be obvious from the above description that the bellows structure constitutes a flexible 45 connection between the float chamber wall and the float arm which is adapted to readily yield to the movements of the float as it rises and falls in response to changes of water level within the float chamber, thus in effect, providing the equivalent of a pivotal connection. Owing to the provision of the internal bellows element 39 in combination with the external bellows element 44, whereby a closed annular chamber between the two is formed, said annular chamber may be 50 filled with a suitable liquid, so that, although the flexing of the structure freely occurs, the bellows structure is internally braced against undue longitudinal contraction and expansion, which, if allowed to occur might prevent proper movement 55 of the float and proper actuation of the switch mechanism which is operated by float movement. The liquid content of the bellows structure is of especial advantage in bracing the latter against contraction or compression in the 60 event high pressure is developed in the boiler and communicated to the float chamber, for, should the bellows structure be subject to contraction of compression from such cause, it might become so rigid that the float would fail to drop upon ab- 65 normal lowering of the water level, and conse- 70 quently timely operation of the switch mechanism might fail under critical conditions and the desired safety function of the apparatus would be defeated.

75 Pivots mounted on a fulcrum stud 46, which

projects from the exterior of the float chamber face wall 27, is a carrier plate 47 upon which is adjustably supported a clip plate 48, the clip arms 49 of which are adapted to embrace and carry a mercury tube contactor switch 50.

Mounted upon bracket lugs 51, with which the float chamber face wall 27 is provided, is a panel 52 having binding posts 53 and 54. One pole, as 55, of the switch 50 is connected, by a flexible conductor 56, to binding post 53, and the other pole, as 57, of switch 50 is connected by a flexible conductor 58 to binding post 54. The cover-cap 29 is provided with suitable coupling means 59 to which may be secured outgoing flexible conduit 60 through which conductors of the electrical circuit to be served by the switch 50 may be led and respectively connected to the binding posts 53 and 54. The actuator finger 43, which extends from the float arm extension 42, is operatively coupled to the pivoted carrier plate 47 by engaging said finger through a perforation 61 with which said carrier plate is provided.

Assuming the switch 50 operates to normally maintain closed an electrical circuit, such e. g. as that serving the fuel burner and delivery mechanism with which boiler 15 is equipped, then the switch and its carrier is so arranged as to normally incline in a direction adapted to dispose its mercury content of the switch in bridging relation to the pole terminals thereof when the float member 30 is in an uplifted position as governed by a normal water level condition in the boiler and float chamber. Such uplifted position of the float member 30 swings downward the actuator finger 43 and down tilts the switch carrier and the switch to such normal closed condition (see Figs. 2 and 3). If water in the boiler and consequently in the float chamber falls below normal desired level, then the float member 30 will drop, thereby swinging upward the actuator finger 43, and consequently thereby uptilting the switch carrier and the switch, so that the mercury content of the latter will move out of bridging relation to the switch pole terminals, thus opening the switch and interrupting the electrical circuit to cause 40 stoppage of fuel burner and delivery operation, until such time as the water in the boiler and float chamber is restored to normal level.

It will be obvious that, if desired, the switch 50 may be arranged to serve an electric circuit 50 controlling the operation of an electrically driven feed water pump, or which controls an electrically actuated feed water admission valve means, rather than the circuit serving the fuel burner and delivery means. It will be understood that the float controlled actuating means per se, including the novel laterally flexible but longitudinally braced double walled bellows structure for pivotally mounting the float arm in such manner as to allow its free end to project exteriorly from the float chamber for co-operation with mechanism desired to be actuated in response to float movements, may be utilized in many other connections and for many purposes in addition to the specific application thereof as a low water control for boilers. It is therefore intended that the invention is to be viewed broadly as to the float controlled actuating means per se.

It will be understood that many widely different embodiments of this invention could be made without departing from the scope thereof. It is therefore intended that all matter contained in the above description or shown in the accom- 75

panying drawings shall be interpreted as illustrative and not in a limiting sense.

Having now described my invention, I claim:—

5. 1. In a control means having a buoyant float operative in a float chamber, said float being provided with an arm having a free end portion projecting exteriorly from said float chamber for cooperation with mechanism to be actuated by float movement, a laterally flexible double 10 walled sealing bellows structure secured to and between the float arm and a wall of said float chamber, said bellows structure providing a sealed annular chamber intermediate its walls, and a liquid mass filling said annular chamber 15 to brace the bellows structure against longitudinal compression.
2. In a control means having a buoyant float operative in a float chamber, said float being provided with an arm having a free end portion 20 projecting exteriorly from said float for cooperation with mechanism to be actuated by float movement, a laterally flexible sealing bellows structure comprising, an internal bellows element having an open outer end and a closed 25 inner end, means to secure the open outer end of said element to the float chamber wall and so as to open exteriorly through the latter, said float arm being secured to the closed inner end of said internal bellows element 30 and the free end portion of said float arm passing outwardly through the latter and its outer open end, an external bellows element concentric to said internal bellows element and forming therewith an intermediate sealed annular 35 chamber, and a liquid mass filling said annular chamber.

3. In a control means having a buoyant float operative in a float chamber, said float being provided with an arm having a free end portion projecting exteriorly from said float chamber, a double walled sealing bellows structure secured to and between the float arm and a wall of said float chamber, said bellows structure providing a sealed annular space intermediate its walls, a liquid mass filling said annular space, and an electric circuit control switch means 10 mounted exteriorly of said float chamber and adapted to be opened and closed by float controlled movement of the exterior end portion of said float arm.

4. In a device of the kind described, a float 15 operative within a float chamber, a float arm, a laterally flexible sealing bellows structure comprising, an internal bellows element having an open outer end and a closed inner end, means to secure the open outer end of said element to the float chamber wall and so as to open exteriorly through the latter, an external bellows element concentric to said internal bellows element and forming therewith an intermediate 20 annular space, a liquid mass filling said annular space, means to secure the closed inner end of said internal bellows element to said float arm, said float arm having an extension passing outwardly through said internal bellows element 25 exteriorly of said float chamber, and an electric circuit control switch means mounted exteriorly of said float chamber and adapted to be opened and closed by float controlled movement of said float arm extension. 30

ERNEST W. LOESSER.
